BOTTLE

George H. McLean, Chicago, Ill., assignor to Owens-Illinois, Inc., Toledo, Ohio, a corporation of Ohio

Filed May 27, 1966, Ser. No. 2,453

Term of patent 14 years

(Cl. D58—6)

The characteristic features of this design reside in the configuration shown in full lines in the drawing.

I claim:

The ornamental design for a bottle, substantially as shown and described.
